(57) CLAIM

The ornamental design for an awning for cruiser flying deck, as shown and described herein.

DESCRIPTION

FIG. 1 is a side view of the awning for cruiser flying deck

1 Claim, 6 Drawing Sheets

embodying my design, the other side being substantially a mirror image thereof;

FIG. 2 is a top plan view thereof;

FIG. 3 is a bottom plan view thereof;

FIG. 4 is a front view thereof;

FIG. 5 is a rear view thereof;

FIG. 6 is a sectional view along line 6—6 in FIG. 2 and showing the transparent window panel in a closed position;

FIG. 7 is a sectional view along line 6—6 in FIG. 2 and showing the transparent window panel in an opened position;

FIG. 8 is an enlarged reference drawing showing the condition of use as viewed from the side;

FIG. 9 is a reference drawing of the condition of use as viewed from the side;

FIG. 10 is a reference drawing of the condition of use as viewed from above; and,

FIG. 11 is a reference drawing of the condition of use as viewed from the front.

The broken line showing of environmental structure in FIGS. 8-11 is for illustrative purposes only and forms no part of the claimed design.
